CLAIM

The ornamental design for a dictation recording device and docking station, as shown and described.

DESCRIPTION

FIG. 1 is a front perspective view of a dictation recording device and docking station showing my new design;

FIG. 2 is rear elevational view of the dictation recording device of FIG. 1, shown separately for clarity of illustration;

FIG. 3 is a left side elevational view of FIG. 1;

FIG. 4 is a front elevational view of FIG. 1;

FIG. 5 is a right side elevational view of FIG. 1;

FIG. 6 is a top plan view of FIG. 1;

FIG. 7 is a rear elevational view of FIG. 1;

FIG. 8 is a left side elevational view of FIG. 2;

FIG. 9 is a front elevational view of FIG. 2;

FIG. 10 is a right side elevational view of FIG. 2;

FIG. 11 is a perspective view of FIG. 2;

FIG. 12 is a top plan view of FIG. 2;

FIG. 13 is a top right perspective view of FIG. 2;

FIG. 14 is a top plan view of a second embodiment of FIG. 12;

FIG. 15 is a left side elevational view of FIG. 14; and,

FIG. 16 is a right side elevational view of FIG. 14.
